CLAIM

The ornamental design for a dive mask, as shown and described.

DESCRIPTION

FIG. 1 is a perspective view of a dive mask showing my new design;

FIG. 2 is a top plan view thereof;

FIG. 3 is a front elevational view thereof;

FIG. 4 is a bottom plan view thereof; and

FIG. 5 is a side elevational view thereof, the opposite side view being a mirror image of that shown.

FIG. 1

FIG. 2

FIG. 3

FIG. 4

FIG. 5
